UNITED STATES PATENT OFFICE.

PETER WHITE, OF ST. LOUIS, MISSOURI.

FIRE-PLUG.

SPECIFICATION forming part of Letters Patent No. 236,290, dated January 4, 1881.

Application filed October 11, 1880. (No model.)

To all whom it may concern:

Be it known that I, PETER WHITE, of St. Louis, Missouri, have made a new and useful Improvement in Fire-Plugs, of which the following is a full, clear, and exact description, reference being had to the annexed drawings, making part of this specification, in which—

Figure 1 is an elevation of the improved plug; Fig. 2, a vertical section; Fig. 3, a vertical section of the upper end of the plug; Fig. 4, a vertical section of the lower end of the plug; Fig. 5, a vertical section of the upper end of the plug, showing the valve-stem as when the valve is open; Fig. 6, a vertical section of the lower end of the plug, showing the valve as when opening; Figs. 7, 8 details, being sectional views of that portion of the plug immediately connected with the waste-valve, and Fig. 9 a horizontal section 20 taken on the line $x x'$ of Fig. 3.

The same letters denote the same parts.

In the present plug the valve opens against the water-pressure, and the waste is discharged through the valve-stem into a chamber 25 in the bottom of the plug, and thence out.

In the drawings, A represents the improved plug, having the inlet B and outlet or outlets C.

The valve D is in the form of a cup-leather. 30 When closed, as seen in Figs. 2, 4, the valve is just within the lower end of the cylinder a; but in opening the valve it is moved downward into a chamber, a', larger in diameter than the cylinder a, as shown in Fig. 6. 35 The valve is attached to the stem E. It is supported from the upper side by means of the plate or washer e; and to enable the water, as the valve is opened, to pass the flange d of the valve, a nut, F, having the flange f, is attached to the valve-stem beneath the valve.

This acts to spread the inflowing stream and to deflect it, in an annular form, to the outer side of the valve-flange d, and to prevent the latter from being flattened against the shell 45 of the plug. When the valve is closed, however, the water pressing between the nut-flange f and the cup-leather causes the valve to become perfectly tight. The valve is operated by means of the screw G, which engages in a 50 socket, E', that is upon the upper end of the valve-stem E.

To prevent the valve and stem from rotating, the socket E' is furnished with ribs e' e', which move in grooves h h, that are in a pendant, H. The latter is made part of or is attached to the shell of the plug. The rotary movement of the screw G thus causes the 55 valve to move up and down in the plug.

The stem E extends beneath the valve, the lower end of the stem and the extension E² 60 being hollow, forming a chamber, I, within the stem, the inlet or inlets i i to which are just above the plate e, and the outlets at i' i'. The extension E² works in a chamber, J, at the bottom of the plug.

To prevent the water from passing from the chamber a' down past the end of the extension E², the latter is furnished with a cup-leather, K, arranged as shown, and above the outlets i' i'.

L represents another valve, (a cup-leather,) 70 attached to the stem l, and working within the extension E².

The operation of this portion of the improvement is as follows: When the valve is opened 75 the lower end of the stem l encounters the bottom of the plug, and the valve L is thereby moved in the extension E² to above the outlets i' i', and to cut off the escape of water through the valve-stem; but when the valve 80 is opened the valve L, being forced by the weight of the water above it, drops below the outlets i' i'. The water then flows from the cylinder a through the stem into the chamber J, and thence is discharged through the outlet 85 j. The two positions of the valve L are shown more distinctly in Figs. 7 and 8.

I claim—

1. The combination of the cylinder a, valve D, stem E E², having the chamber I and passages i i', chamber J, valves K L, and stem l, substantially as described.

2. The combination of the chamber J, having the outlet j, the extension E², having the chamber I and outlets i i', valve K, valve L, 95 and stem l, substantially as described.

3. The combination, in a fire-plug or valve, of the extension E², having the chamber I and outlets i i', and the valve L and stem l, substantially as described.

4. The combination, in a fire-plug, of the cylinder a, chamber a', larger in diameter 100

than the said cylinder, nut F, and the cup-leather valve D, said valve opening against the pressure and into the chamber a', substantially as described.

5 5. The combination of the cylinder a, valves D K, stem E E², having the chamber I and passageways i i, and the chamber J, having the outlet j, substantially as described.

6. The combination of the cylinder a, valve D, stem E, socket E', having the ribs e' e, pendant H, having the grooves h h, and the screw G, substantially as described.

PETER WHITE.
